WARP KNITTING MACHINE

Rudolph Bassist, New York, N. Y., assignor of forty-five per cent to himself, ten per cent to Harold H. Stern, twenty-two and one-half per cent to Edith Abrams, and twenty-two and one-half per cent to Edith April, New York, N. Y.

Application July 3, 1943, Serial No. 493,382

19 Claims. (Cl. 66—86)

My present invention relates generally to knitting machines and has particular reference to so-called warp knitting machines.

While certain phases of my invention are not necessarily restricted to their applicability to any particular kind of warp knitting machine, the general object of the invention is to provide certain improvements in high-speed knitting machines of the so-called "Tricot" type. These machines are of relatively high gauge, employing approximately 28 to 34 needles per inch, and operating at rates of speed up to about 600 courses or stitches per minute.

In a warp knitting machine, the yarn is initially wound on one or more warp beams and is directed in parallel rows to a bank of needles which operate in a predetermined intermittent manner to interengage the threads to produce a knitted fabric of the "jersey" type. The yarn is directed to the needles by one or more guide bars through which the individual strands are threaded and by means of which the threads are looped around the needles or otherwise subjected to their operation, in a predetermined manner and sequence depending upon the particular pattern or style of knitted fabric which is to be produced.

In order that my invention may be better understood, I will preface this description by outlining, in a general way, the mode of operation and cooperation of the main parts of a warp knitting machine.

A main driving shaft (hereinafter referred to as a cam shaft) is associated with means for intermittently moving the needles through the knitting cycle. Generally speaking, this movement is an up-and-down movement. Thread is suitably looped around the needles while they are in their upward positions, and when the needles move downwardly they perform a knitting operation, with the aid of a "presser bar," a "sinker," and other suitable auxiliary parts which are well known per se. Each guide bar is provided with a corresponding number of needles through which the strands coming from the warp beam are threaded. Actuated by the cam shaft is a means for imparting a predetermined intermittent movement to the guide-bar, one component of movement being in a substantially forward-and-back direction, the other component of movement being longitudinal. These movements of the guide-bar are so timed and controlled, relative to the needle operation, that the strands are suitably looped around or otherwise subjected to the action of the needles in accordance with a predetermined pattern.

For example, assuming that only one warp beam is employed, the guide-bar may be moved so as to loop a strand around one needle during one course, around an adjacent needle during the next course, then around the first-mentioned needle again during the third course, and so on. Or, depending upon the fabric desired, the guide-bar may loop a strand around one needle for one course, then shift longitudinally and loop the strand around a needle at a distance from the first for the second course, and then shift again either in the same or reverse direction to loop the strand around a third selected needle for the third course, and so on. A large number of 15 different optional cycles are possible, depending upon the results desired in the finished product. In each case, however, the longitudinal movement of the guide-bar requires that a certain amount of yarn be made available to it, the exact amount being dependent upon the extent of the longitudinal movement of the guide-bar; and during each forward-and-back or swinging movement of the guide-bar a relatively reduced amount of thread should be made available to it. The 20 greater the accuracy with which the yarn feed corresponds to the moment-to-moment fluctuating yarn demands of the guide-bar, the more smoothly and efficiently will the machine operate.

The machine may employ either one, two or three warp beams, possibly more. The simplest type of fabric is produced by the employment of only a single warp beam. A different type of fabric would result from the employment of two warp beams, it being understood that there is usually a separate guide-bar for each warp beam. Where a "filler" thread, or more accurately, an unknitted warp thread, is to be associated with the fabric for the purpose of forming loops or other ornamental effects, it is customary to employ one or two warp beams to produce the so-called "ground fabric," and to employ a separate warp beam for the additional warp thread. In such case, the guide-bar through which the latter strands are threaded will have its movements so controlled that these strands are brought into proper relationship to the needles, and to the strands of the ground fabric, in a predetermined manner.

For the sake of simplicity, the features of the 50 present invention will be described in connection with a single warp beam and a single guide-bar, although it will be understood, as hereinbefore pointed out, that more than one warp beam may be employed if necessary or desirable.

55 In the conventional type of warp knitting ma-

chine, one of the shortcomings has arisen from the fact that the threads are drawn from the warp beam by a pulling action initiated by the needles themselves and by the guide-bar which controls the disposition of the yarn with respect to the needles. The warp beam is generally provided with some sort of brake or equivalent clutch mechanism operated by the pull of the yarn, whereby the warp beam is released for rotation whenever the knitting cycle calls for thread, and whereby it is secured against rotation in the interim periods. This arrangement has numerous disadvantages and imposes severe limitations upon the knitting operations. For example, the interdependence between yarn feed and warp beam rotation restricts the types of fabric that may be produced. Also, any stopping or starting of the machine as a whole produces an irregularity in the knitting operation whereby an undesirable line or streak known as a "stop-mark" is produced in the fabric. The latter disadvantage often causes material impairment of the commercial value of the fabric, and it manifests itself most frequently in the high-speed machines to which my invention has primary reference, and in cases where the yarn is of the relatively slippery character of rayon or the like.

In my Patent No. 2,303,903, I disclosed a means whereby these disadvantages, and others, are successfully overcome, one of the characterising features of the improved machine residing in the fact that the warp beam is continuously rotated in yarn-feeding direction in a predetermined timed relationship with respect to the knitting cycle, but independent of any pulling action upon or by the yarn itself.

In my co-pending patent application Ser. No. 467,188 (now Patent No. 2,334,058), I described a further improvement and refinement of this general type of machine, whereby there is imposed upon a continuously rotating warp beam a regular fluctuating component of movement intended to synchronize the thread feed with the fluctuating requirements of the needles and guide-bars. I disclosed the employment, in the warp beam transmission, of a mechanism (exemplified by a pair of meshing non-circular gears) which comprises rotating driving and driven members wherein a fluctuating angular velocity is imparted to the driven member relative to that of the driving member.

This type of mechanism, while improving the synchronization between the thread feed and guide-bar demands, is subject to certain limitations arising from the fact that any selected set of meshing non-circular gears, or other equivalent mechanism of this character, is restricted to a fluctuating output of too regular a character.

It is the principal object of the present invention to provide certain further improvements which permit an even wider range of adjustments to be effected in the timing of the thread feed and its synchronization with the yarn requirements of the guide-bars and needles. As a result, a warp knitting machine incorporating the structural innovations of the present invention is capable of producing a wider variety of different knitted fabrics and patterns, many of which have not heretofore been capable of manufacture at all by means of a warp knitting machine. By properly controlling the various adjustments which are now made available, a warp knitting machine is capable of operating smoothly and efficiently, at high speeds and for long periods

of time, to produce fabrics having widely different and unique patterns and designs, the thread feed being always accurately correlated with the varying moment-to-moment yarn requirements of the knitting instrumentalities.

Briefly, the present improvements reside in the provision of at least one differential interposed in the driving transmission between the cam shaft and the warp beam, the output being in driving relation to the warp beam, the inputs of the differential being operatively connected to one or more regulatory means for imposing the desired components of movement upon the warp beam.

10 The machine preferably includes also an adjustable change-speed device of the character described and illustrated in my aforementioned patent, this device being of the character which comprises rotating driving and driven members whose relative speeds of rotation are adjustable during continuous operation thereof. This device, interposed in the transmission to the warp beam, affords a further opportunity for controlling and adjusting the warp beam movements and permits the employment of a second differential whose output is operatively connected to the adjusting member so that various regulatory means may be operatively connected to permit manual or automatic adjustments in accordance with a predetermined plan.

30 I achieve the foregoing general objects and advantages, and I provide for the embodiment of the foregoing features, and others, in a practical machine, in the manner illustratively exemplified in the accompanying drawings in which:

Figure 1 is a diagrammatic front elevational view of a warp knitting machine employing certain of the features of the present invention;

Figure 2 is a fragmentary enlarged view of diagrammatic character of a pattern control such as that shown at the right end of Figure 1, illustrating the mechanism which it may actuate in accordance with the present invention;

Figure 3 is a diagrammatic view of the arrangement of mechanism in one embodiment of the present invention;

Figure 4 is a diagrammatic view showing one type of regulatory means for "Differential No. 1" shown in Figure 3;

Figure 5 is a diagrammatic view similar to Figure 3 showing a modification;

Figure 6 is a diagrammatic view similar to Figure 5 showing another modification; and

Figures 7 and 8 are diagrammatic views showing further modifications, respectively, in which no change-speed device is employed.

Referring for the moment to Figure 1, I have illustrated certain parts of a warp knitting machine of the character to which my present invention has primary reference. Mounted within the confines of a suitable framework 20 is a main driving shaft or cam shaft 21. This shaft extends in a longitudinal direction with respect to the machine as a whole, and it is driven by a motor or by any other suitable motive power (not shown) in well-known fashion. It carries such cams and other driving elements as may be required to transmit predetermined driving impulses to the various elements of the machine. At 22 I have indicated a warp beam which may be mounted in any suitable manner for rotation about an axis longitudinally arranged with respect to the machine. In the conventional machine, this warp beam (together with one or more additional warp beams) is mounted upon the

framework 26, usually in the upper region of the machine. In accordance with my present invention, however, it is possible to mount this warp beam in an independent support or framework (not shown) at the rear of the machine. This is of great importance since much larger warp beams may be employed, and since the tremendous weight of the beams is thus removed from any possibility of impairing the smooth high-speed operation of the knitting machine with a minimum of vibration.

In accordance with my invention, this warp beam is continuously rotated by means of a transmission which ultimately derives its motive power from the cam shaft 21. This transmission may assume various forms, hereinafter to be explained in greater detail.

Mounted in the machine in well-known manner is a needle-bar 34. Projecting upwardly from it are needles by means of which the knitting operation is performed. This needle bar is intermittently operated by the cam shaft 21 to move the needles through the desired knitting cycle which is well known per se. Any suitable mechanism may be employed for accomplishing this purpose, as illustratively exemplified in Figure 3 of my aforementioned patent 2,334,058.

Mounted in proximity to the needles is a guide-bar 42 which carries a plurality of downwardly projecting teeth or equivalent elements which are adapted to move in a forward-and-back direction within the spaces between the needles of the needle bar. This component of movement of the guide-bar is under the control of the cam shaft 21, by means of any suitable well-known mechanism illustratively exemplified in Figure 2 of my aforementioned patent 2,334,058.

The guide-bar is usually provided with brackets such as those shown at 51, these brackets being articulated to hangers 50 in such a manner that the guide-bar 42 can also be subjected to longitudinal shifting movements. These movements are also under the control of the cam shaft 21, through the intermediary of a suitable drive mechanism such as a worm 52 and a worm wheel 53. This drive mechanism actuates a suitable pattern control which I have chosen to illustrate in the form of a pattern wheel 55 mounted on the shaft 54 of the worm wheel 53, the pattern wheel being thus slowly and continuously rotated. The periphery of the pattern wheel 55 is provided with a predetermined series of raised and depressed portions, and the end of the guide-bar is provided with a follower 57 which is constantly pressed against the periphery of the pattern wheel in a yieldable manner by means of the spring 58 or the like. Accordingly, certain longitudinal movements are imparted to the guide-bar in a predetermined sequence and of predetermined magnitudes as the follower 57 is pushed to the left or right under the actions of the pattern wheel 55 and the spring 58.

The projections and depressions of the pattern wheel may be integral portions of the wheel or, as is preferable, they may be provided for by means of suitable elements or links separably mounted on the pattern wheel in predetermined spaced relationships. A pattern wheel of this general character is well known per se, and is merely illustrative of a general type of pattern control which may be employed for the purpose. For example, a continuously moving chain, or equivalent instrumentality, may be driven by the cam shaft in a similar manner, the chain being made up of separable links or the like to form any

desired length, and serving to control the longitudinal movements of the guide-bar by means of selected contours, projections, depressions, or the like, on the periphery or sides of the links or other equivalent elements.

The term "pattern control" as used herein and in the appended claims, is intended to refer generally to an alterable pattern wheel or chain or equivalent instrumentality of this general character.

The yarn from the warp beam is directed in suitable fashion to the guide-bar, each strand being threaded through one of the teeth of the guide-bar. The movements of the guide-bar, both forward-and-back and longitudinal, control the disposition of this yarn with respect to the needles, looping it successively around predetermined needles, or otherwise bringing it into the range of operation of the needles, or into association with strands emanating from other warp beams, all in accordance with a predetermined plan or pattern which manifests itself in the operative contour of the pattern wheel 55. Simultaneously, the needles, operating in timed relationship with the guide-bar, perform the actual knitting operation, a knitted fabric being thus produced, course by course, and being wound up on a suitable roller (not shown) at the forward portion of the machine.

It is obvious that this mode of operation imposes varying requirements upon the thread feed. Thus, whenever the guide-bar is moving to loop the strands around the needles, or otherwise to bring the strands into the range of the knitting operation, yarn must be made available; and during those interim periods during which the needles are knitting or otherwise incorporating the yarn into the fabric, the demand for thread feed is momentarily diminished. Similarly, whenever the guide-bar is moving longitudinally through relatively large distances (skipping for example, from one needle to another selected needle some distance away), the demand for yarn is correspondingly greater than during other longitudinal movements of the guide-bar which are of lesser magnitude. In accordance with my present invention, it is possible to conform the yarn feed with considerable accuracy to these varying requirements, notwithstanding the fact that the warp beam is continuously rotated quite independently of any clutch or brake mechanism depending for its operation upon any pulling effect of the yarn itself.

The general manner in which the desired synchronization of the yarn feed and yarn requirements may be accomplished by means of the present invention is indicated in a diagrammatic fashion in Figure 3. It will be observed that the warp beam 22 is driven by a transmission which includes a speed reducer 24 and several controllable or regulatory elements. One of these is the change-speed device 23 which may be of any well-known character, e. g., a conventional "Reeve's drive." The details of such a drive are well known per se and are exemplified in Figure 5 of my aforementioned Patent 2,334,058. Briefly, the drive comprises a pulley member mounted on the driving shaft 27, a pulley member mounted on the driven shaft 28, and a rotatable control member or shaft 70. The driving and driven members are connected by a belt and comprise pulleys of suitable character whose effective diameters are relatively adjustable by means of regulatory rotations of the control shaft 70 in one direction or the other, whereby any speed

relationship (within the range which the device affords) may be brought about, depending upon requirements, during a continuous operation of the transmission.

The output or driving shaft 28 of the change-speed device is operatively connected to the speed reducer. The input or driving shaft 27 is under the control of selected regulatory means, and the adjustment shaft 70 is similarly under the control of selected regulatory means. In Figure 3, I have shown a preferred arrangement in which a differential 125 has its output 126 operatively connected (e. g., by meshing bevelled gears 127), to the driving member 21 of the change-speed device, and in which a similar differential 75 has its output shaft 78 operatively connected in a similar manner to the control shaft 70 of the change-speed device. In the present drawings, the differential 125 is designated as "Differential No. 1" while differential 75 is designated "Differential No. 2."

Each of the differentials is of conventional well-known character such as that which is commonly employed, for example, in association with the rear axle of an automobile. Since the internal parts of the motive power of such a differential mechanism are well known, I have deemed it sufficient merely to indicate two input driving shafts in each case and a single output shaft. Using the automobile analogy, the input shafts correspond to those which commonly extend respectively to the rear wheels of the automobile, while the output shaft corresponds to the transmission shaft extending to the engine. However, whereas the automobile differential imposes the input power through the transmission shaft and derives the corresponding output in equal or varying degrees at the rear wheels, each of the present differential mechanisms is employed in a reverse fashion. In the case of the differential 125, a regulatory motive power is applied to one or both of the input shafts 128 and 129 while the resultant effect is withdrawn from the output shaft 126 and transmitted to the change-speed device. In the case of the differential 75, a regulatory input is operatively connected to one or both of the input shafts 76 and 77, while the resultant output is derived from the output shaft 78 which is operatively connected to the adjusting member 70 of the change-speed device.

The inputs to the shaft 76 and 77 of "Differential No. 2," may be, for example, of the character illustrated and described in my aforementioned Patent 2,334,058 whereby the shaft 76 derives motive power from a reversible electrical motor or the like, whose operation is controlled by a suitable pattern control, while the shaft 77 derives motive power from a mechanism which is automatically adjusted to compensate for the diminishing diameter of the warp beam as thread is withdrawn therefrom.

The motive power applied to the input shafts 128 and 129 of "Differential No. 1" may be, for example, of the character illustrated most clearly in Figures 2 and 4. Referring to Figure 4, it will be observed that I have shown the input shaft 128 operatively connected (e. g., by bevelled gears 130 or the like) with a pair of meshing non-circular gears 131. I have chosen to show these gears as being substantially elliptical in contour. These gears are an illustrative exemplification of a type of mechanism in which a predetermined rotation of the driving member (the upper one shown in Figure 4) imposes upon the driven member an angular velocity of predetermined fluctuating character. The driving member of this mechanism is connected in any suitable fashion with the cam shaft of the knitting machine, as indicated at 132. By properly designing and selecting the driving and driven members of this mechanism, such as the elliptical gears 131 illustratively shown in Figure 4, a predetermined rotation of the cam shaft 21 of the knitting machine at uniform angular velocity can be caused to impose upon the input shaft 128 of "Differential No. 1," and ultimately upon the driven warp beam 22, a fluctuating component of movement which conforms with certain basic fluctuating demands of the needles and the guide-bar, thus "setting the tempo," as it were, of the yarn feed.

The input shaft 129 of "Differential No. 1" may derive a regulatory power by means of a mechanism such as shown most clearly in Figure 2. Mounted on a shaft 133 is a ratchet wheel 134 with which two driving pawls 135 are associated. Driving links 136 connect these pawls with a reciprocating member 137 which is constantly urged in one direction by a spring 138 or the like and which carries a follower 139 which rides upon a suitable pattern control 140 driven by the cam shaft 21. This pattern control is of the same general character as that shown at 55 in Figure 1, and may in fact consist of this self-same instrumentality. I have shown for example how the reciprocated member 137 may be directly connected to a guide-bar 141 to control the longitudinal back-and-forth movements of the guide-bar as the follower 139 rides upon the projections and depressions, or equivalent convolutions, of the pattern control 140. During these movements of the reciprocating member 137, the ratchet wheel 134 is intermittently advanced in the direction of the arrow shown in Figure 2, regardless of the direction of movement of the member 137. Thus when the follower 139 encounters a projection which moves the member 137 to the left (as viewed in Figure 2) the lower pawl 135 advances the ratchet 134 while the upper pawl rides freely without effect upon the ratchet; and whenever the follower 139 encounters a depression which permits the spring 138 to move the member 137 to the right (as viewed in Figure 2) the upper pawl 135 becomes operative to give an impetus to the ratchet 134 while the lower pawl remains ineffective.

It will be understood that the pattern control which actuates the ratchet 134 need not necessarily be the same pattern control as that which actuates the guide-bar 141. Two separate pattern controls may be employed, if desired. In either case, however, the pattern controls are so designed that the movements imparted to the ratchet 134 are correlated to the longitudinal shifting movements of the guide-bar in predetermined manner, so that, for example, if the guide-bar moves for a relatively long distance, the ratchet 134 will move by a correspondingly greater amount, while if the guide-bar moves through a smaller distance the ratchet 134 will rotate through a correspondingly smaller amount.

It may also be desirable under certain circumstances to use two separate pattern controls but to arrange them on a single instrumentality. For example, a pattern control may be employed which actuates the guide-bar by means of a follower riding on the periphery of a wheel such as that shown at 55 in Figure 1 or at 140 in Figure 2, while the actuation of the ratchet mechanism may simultaneously be controlled by a follower which rides in a cam groove formed in the side

wall of the pattern wheel. The guide-bar movements, in such a case, would be responsive to the elevations and depressions on the periphery of the pattern wheel, a spring such as that shown at 58 in Figure 1 or at 138 in Figure 2 serving to yieldably hold the follower down against the pattern control. The ratchet movements, however, would require no such springy assistance and would be governed solely by the convolutions of the cam groove formed in the pattern wheel.

By operatively connecting the shaft 133 (through the intermediary of bevelled gears 142 or the like) with the input shaft 129 of "Differential No. 1," as indicated in Figure 4, a fluctuating component of movement is imposed upon the output 126 of this differential (hence ultimately upon the driven warp beam 22) which is supplemental to any component of movement imposed upon the other input 128 of this differential. By properly selecting the regulatory means which thus simultaneously transmit different components of movement to the differential, any of a large variety of accurately controllable resultant movements may be transmitted from the output of the differential to the balance of the transmission mechanism which leads ultimately to the warp beam.

As a specific example, let it be assumed that the fabric being knitted is one in which the major portion of the fabric consists of a simple uniform pattern, while a special design (requiring unusually extensive guide-bar movements) is periodically to be knitted into the fabric. During the knitting of the simple pattern, the elliptical gears 131 continuously impose upon the warp beam a fluctuating movement which feeds the yarn in synchronism with the course-by-course fluctuating demands of the guide-bar, and during this time, the rotative movement of the ratchet 134 is of uniform character since the guide-bar is moving back and forth through more or less uniform distances. When the time is reached when the guide-bar is moved through the unusually great distances to produce the special design or pattern, a correspondingly greater movement is imparted to the ratchet 134, and this added increment manifests itself in greater movement of the warp beam 22 by virtue of the fact that the increased movement of the ratchet 134 is superimposed through the differential 125, upon the normal fluctuations imposed by the elliptical gears. At all times, therefore, regardless of the special or unusual character of the design or pattern which is being knitted by the machine, the rotation of the warp beam 22 is accurately in synchronism with the moment-to-moment demands of the guide-bar for varying or fluctuating amounts of yarn.

In Figures 5 and 6 I have illustrated two possible modifications of the transmission in which "Differential No. 1" has been completely omitted. In Figure 5, for example, the transmission is the same as in Figure 3 except that the elliptical gears 131 (or equivalent mechanism) are connected directly to the driving shaft 27 of the change-speed device 23. In other respects the elements of Figure 5 are the same as those shown in Figure 3, and the same reference numerals have therefore been applied. This arrangement of parts is identical with one of the embodiments illustrated in my aforementioned Patent 2,334-058 and is shown in the present drawings merely for comparative purposes.

The regularity of the fluctuating component of movement imposed by the elliptical gears (as

arranged in Figure 5 and in my aforementioned Patent 2,334,058) has certain disadvantages and limitations. In accordance with my present invention, these limitations may be avoided by supplementing the elliptical gears of Figure 5 with the mechanism shown in Figure 2. This results in an arrangement of parts as shown in Figure 6. In this figure, the shaft 133 of the mechanism of Figure 2 is connected directly to the driving member 27 of the change-speed device 23. The other elements shown in Figure 6 are the same as in Figures 3 and 5 and the same reference numerals have therefore been applied. In the arrangement of Figure 6, the fluctuating movements imposed upon the driving member 27 are more accurately in synchronism with the fluctuating demands of the guide-bar regardless of the varying nature or complexity of the guide-bar movements.

20 The use of "Differential No. 1" as shown in Figures 3 and 4 is a preferable arrangement, because it simultaneously affords the advantages of the elliptical gears or equivalent mechanism (as described more fully in my aforementioned Patent 2,334,058), and the mechanism of Figure 2 of the present drawings which responds so completely to the desired pattern control. This latter mechanism however, has certain advantages which may be independently resorted to, as indicated in 25 Figure 6, and the arrangement of Figure 6 is therefore illustrated to show the possibility, under certain circumstances, of employing the mechanism of Figure 2 without necessarily employing either a differential or any elliptical gears or equivalent mechanism.

30 In Figures 7 and 8, I have illustrated several modifications in which the change-speed device is dispensed with. The use of this device is highly desirable, since it affords an additional 35 opportunity for imposing various selected regulations to the yarn feed. However, under certain circumstances, the transmission may be employed without the change-speed device.

In Figure 7, for example, I have shown "Differential No. 1" connected directly to the speed reducer 24 through the intermediary of meshing gears 142 or the like. In this case, the inputs of the differential may be connected to any desired 45 regulatory means such as those shown, by way of 50 example, in Figure 4.

In Figure 8, I have shown the manner in which the mechanism of Figure 2 may be operatively connected directly to the speed reducer 24 by means of meshing gears 143. This is the simplest 55 arrangement under which the variations of a pattern control may be caused to bring about a corresponding pattern of movement of the warp beam.

It will thus be observed that I have provided 60 various means whereby selected regulating devices may be employed for the purpose of achieving the basic objective. Where a change-speed device is included in the transmission, and where two differentials are employed, as shown most 65 clearly in Figure 3, an opportunity is afforded for controlling the warp beam movements with great accuracy and in accordance with any of a large number of different predetermined patterns. It will be understood, of course, that the differential 70 may in each case comprise more than two input shafts, and that any suitable regulatory means may be operatively connected to one or more of the inputs. For example, while I have referred to the "diameter control" as being applied to the input shaft 77 of "Differential No. 2," this control

might under certain circumstances be operatively connected to one of the inputs of "Differential No. 1." Or, one of the inputs of one or the other of the differentials might be operatively connected to a manual control by means of which certain added increments of movement could be manually contributed to the resultant movements of the warp beam to compensate for possible extra requirements of certain special circumstances or periods of operation, as for example in the initial starting of the machine from a period of complete rest.

If desired, it might prove useful under certain circumstances to arrange two or more differentials in series relationship, the ultimate objective being in each case to achieve a resultant fluctuating movement of the warp beam which is as accurately as possible responsive to the moment-to-moment fluctuating requirements of the guide-bar.

It will also be understood that the mechanically-operated ratchet mechanism shown in Figure 2 is offered merely by way of example and that any ratchet mechanism or equivalent instrumentality might be employed for the same purpose, whether driven or controlled electrically, electronically, electromagnetically, by hydraulic means, or otherwise.

In general, it will be understood that the details herein described and illustrated may be modified by those skilled in the art without departing from the spirit and scope of the invention as expressed in the appended claims. It is therefore intended that these details be interpreted as illustrative and not in a limiting sense.

Having thus described my invention and illustrated its use, what I claim as new and desire to secure by Letters Patent is:

1. In a warp knitting machine including needles, a warp beam furnishing yarn thereto, a cam shaft for moving the needles through the knitting cycle, and a movable guide-bar controlling the disposition of said yarn with respect to the needles; a driving transmission from the cam shaft to said warp beam; mechanism in said transmission for imposing a regular fluctuating component of movement upon the warp beam; an alterable pattern control driven by the cam shaft; and means in said transmission actuated by said pattern control for imposing a supplemental fluctuating component of movement upon the warp beam.

2. In a warp knitting machine including needles, a warp beam furnishing yarn thereto, a cam shaft for moving the needles through the knitting cycle, and a movable guide-bar controlling the disposition of said yarn with respect to the needles; a driving transmission from the cam shaft to said warp beam; mechanism in said transmission for imposing a regular fluctuating component of movement upon the warp beam, said mechanism being of the character which comprises rotating driving and driven members wherein a fluctuating angular velocity is imparted to the driven member relative to that of the driving member; an alterable pattern control driven by the cam shaft; and means in said transmission actuated by said pattern control for imposing a supplemental fluctuating component of movement upon the warp beam.

3. In a warp knitting machine, the combination set forth in claim 2, said mechanism comprising a pair of meshing non-circular gears.

4. In a warp knitting machine including needles, a warp beam furnishing yarn thereto,

a cam shaft for moving the needles through the knitting cycle, and a movable guide-bar controlling the disposition of said yarn with respect to the needles; a driving transmission from the cam shaft to said warp beam; mechanism in said transmission for imposing a regular fluctuating component of movement upon the warp beam; an alterable pattern control driven by the cam shaft; means in said transmission actuated by said pattern control for imposing a supplemental fluctuating component of movement upon the warp beam; and means also actuated by said pattern control for intermittently moving said guide-bar in cooperative relation to the needle movements.

5. In a warp knitting machine, the combination set forth in claim 1, said transmission including a differential whose output is in driving relation to the warp beam, one input of the differential being operatively connected to said mechanism, another input of the differential being operatively connected to said means which is actuated by the pattern control.

6. In a warp knitting machine, the combination set forth in claim 1, said transmission including an adjustable change-speed device and a differential, said device comprising rotating driving and driven members whose relative speeds of rotation are adjustable during continuous operation thereof, the driven member being in driving relation to the warp beam, the driving member being operatively connected to the output of said differential, one input of the differential being operatively connected to said mechanism, another input of the differential being operatively connected to said means which is actuated by the pattern control.

7. In a warp knitting machine, the combination set forth in claim 1, said transmission including an adjustable change-speed device and a differential, said device comprising rotating driving and driven members whose relative speeds of rotation are governed by rotation of an adjusting member, the driven member being in driving relation to the warp beam, the driving member being operatively connected to the output of said differential, one input of the differential being operatively connected to said mechanism, another input of the differential being operatively connected to said means which is actuated by the pattern control; and means for automatically rotating said adjusting member in accordance with a predetermined plan during continuous operation of said transmission.

8. In a warp knitting machine, the combination set forth in claim 1, said transmission including an adjustable change-speed device and a differential, said device comprising rotating driving and driven members whose relative speeds of rotation are governed by rotation of an adjusting member, the driven member being in driving relation to the warp beam, the driving member being operatively connected to the output of said differential, one input of the differential being operatively connected to said mechanism, another input of the differential being operatively connected to said means which is actuated by the pattern control; and means for automatically rotating said adjusting member in accordance with a predetermined plan during continuous operation of said transmission, said last-named means comprising a second differential whose output is operatively connected to said adjusting member, whereby selected regulatory means may be operatively connected to

one or more of the inputs of said second differential.

9. In a warp knitting machine including needles, a warp beam furnishing yarn thereto, a cam shaft for moving the needles through the knitting cycle, and a movable guide-bar controlling the disposition of said yarn with respect to the needles: an alterable pattern control driven by the cam shaft; and means actuated by said pattern control for imposing upon the warp beam a fluctuating component of movement which corresponds to the fluctuating demands for yarn of said guide-bar; said means comprising a ratchet operatively connected in driving relation to the warp beam, and a driving pawl actuated by said pattern control.

10. In a warp knitting machine including needles, a warp beam furnishing yarn thereto, a cam shaft for moving the needles through the knitting cycle, and a movable guide-bar controlling the disposition of said yarn with respect to the needles: an alterable pattern control driven by the cam shaft; means actuated by said pattern control for intermittently moving said guide-bar in cooperative relation to the needle movements; and means also actuated by said pattern control for imposing upon the warp beam a fluctuating component of movement which corresponds to the fluctuating demands for yarn of said guide-bar.

11. In a warp knitting machine including needles, a warp beam furnishing yarn thereto, a cam shaft for moving the needles through the knitting cycle, and a movable guide-bar controlling the disposition of said yarn with respect to the needles: an alterable pattern control driven by the cam shaft; an adjustable change-speed device comprising rotating driving and driven members whose relative speeds of rotation are adjustable during continuous operation thereof, the driven member being in driving relation to the warp beam; and means actuated by said pattern control for imposing upon the driving member of said change-speed device a fluctuating component of movement which corresponds to the fluctuating demands for yarn of said guide-bar.

12. In a warp knitting machine including needles, a warp beam furnishing yarn thereto, a cam shaft for moving the needles through the knitting cycle, and a movable guide-bar controlling the disposition of said yarn with respect to the needles: an alterable pattern control driven by the cam shaft; an adjustable change-speed device comprising rotating driving and driven members whose relative speeds of rotation are adjustable during continuous operation thereof, the driven member being in driving relation to the warp beams; means actuated by said pattern control for intermittently moving said guide-bar in cooperative relation to the needle movements; and means also actuated by said pattern control for imposing upon the driving member of said change-speed device a fluctuating component of movement which corresponds to the fluctuating demands for yarn of said guide-bar.

13. In a warp knitting machine including needles, a warp beam furnishing yarn thereto, a cam shaft for moving the needles through the knitting cycle, and a movable guide-bar controlling the disposition of said yarn with respect to the needles: an alterable pattern control driven by the cam shaft; a differential whose output is in driving relation to the warp beam; and means actuated by said pattern control for imposing a

fluctuating component of movement upon one input of said differential; whereby selected regulatory means may be operatively connected to one or more other inputs of said differential.

14. In a warp knitting machine including needles, a warp beam furnishing yarn thereto, a cam shaft for moving the needles through the knitting cycle, and a movable guide-bar controlling the disposition of said yarn with respect to the needles: a driving transmission from the cam shaft to the warp beam; said transmission including a differential whose output is in driving relation to the warp beam; and a mechanism driven by the cam shaft for imposing a regular fluctuating component of movement upon one input of said differential; whereby selected regulatory means may be operatively connected to one or more other inputs of said differential.

15. In a warp knitting machine including needles, a warp beam furnishing yarn thereto, a cam shaft for moving the needles through the knitting cycle, and a movable guide-bar controlling the disposition of said yarn with respect to the needles: a driving transmission from the cam shaft to the warp beam; said transmission including a differential whose output is in driving relation to the warp beam; and a mechanism driven by the cam shaft for imposing a regular fluctuating component of movement upon one input of said differential, said mechanism being of the character which comprises rotating driving and driven members wherein a fluctuating angular velocity is imparted to the driven member relative to that of the driving member; whereby selected regulatory means may be operatively connected to one or more other inputs of said differential.

16. In a warp knitting machine, the combination set forth in claim 15, said mechanism comprising a pair of meshing non-circular gears.

17. In a warp knitting machine including needles, a warp beam furnishing yarn thereto, a cam shaft for moving the needles through the knitting cycle, and a movable guide-bar controlling the disposition of said yarn with respect to the needles: a driving transmission from the cam shaft to said warp beam, said transmission including an adjustable change-speed device and a differential, said device comprising rotating driving and driven members whose relative speeds of rotation are adjustable during continuous operation thereof, the driven member being in driving relation to the warp beam, the driving member being operatively connected to the output of said differential; and a mechanism driven by the cam shaft for imposing a regular fluctuating component of movement upon one input of said differential; whereby selected regulatory means may be operatively connected to one or more other inputs of said differential.

18. In a warp knitting machine including needles, a warp beam furnishing yarn thereto, a cam shaft for moving the needles through the knitting cycle, and a movable guide-bar controlling the disposition of said yarn with respect to the needles: a driving transmission from the cam shaft to said warp beam, said transmission including an adjustable change-speed device and a differential, said device comprising rotating driving members whose relative speeds of rotation are governed by rotation of an adjusting member, the driven member being in driving relation to the warp beam, the driving member being operatively connected to the output of said differential; a mechanism driven by the cam shaft for imposing

a regular fluctuating component of movement upon one input of said differential, whereby selected regulatory means may be operatively connected to one or more other inputs of said differential; and means for automatically rotating said adjusting member in accordance with a predetermined plan during continuous operation of said transmission.

19. In a warp knitting machine including needles, a warp beam furnishing yarn thereto, a cam shaft for moving the needles through the knitting cycle, and a movable guide-bar controlling the disposition of said yarn with respect to the needles; a driving transmission from the cam shaft to said warp beam, said transmission including an adjustable change-speed device and a differential, said device comprising rotating driving and driven members whose relative speeds of rotation are governed by rotation of an adjusting

member, the driven member being in driving relation to the warp beam, the driving member being operatively connected to the output of said differential; a mechanism driven by the cam shaft for imposing a regular fluctuating component of movement upon on input of said differential, whereby selected regulatory means may be operatively connected to one or more other inputs of said differential; and means for automatically rotating said adjusting member in accordance with a predetermined plan during continuous operation of said transmission, said last-named means comprising a second differential whose output is operatively connected to said adjusting member, whereby selected regulatory means may be operatively connected to one or more of the inputs of said second differential.

RUDOLPH BASSIST.
